UNITED STATES PATENT OFFICE.

JOHN F. SANDERS, OF ROSEBURG, OREGON, ASSIGNEE TO OLIVER P. COSHOW, OF ROSEBURG, OREGON.

ELECTRODE FOR GENERATING PURE OXYGEN.

1,218,584.

Specification of Letters Patent.

Patented Mar. 6, 1917.

No Drawing.

Application filed August 4, 1915. Serial No. 43,609.

To all whom it may concern:

Be it known that I, JOHN F. SANDERS, a citizen of the United States, residing in the city of Roseburg, in the county of Douglas 5 and State of Oregon, have invented certain new and useful Improvements in Electrodes for Generating Pure Oxygen; and I do hereby declare that the following is a full, clear, and exact description of the invention, which 10 will enable others skilled in the art to which it pertains to use the same.

The object of my invention is to produce pure oxygen, and in such quantities as may be required on board a submarine boat while 15 under the water. However, I do not wish to limit this invention exclusively to the use of submarine boats, as it also may be used for other purposes.

To make this subject clear, I wish to state 20 here some well established facts regarding the atmospheric air. It consists, on an average, in volume, of 20 per cent. of oxygen and 77 per cent. of nitrogen, and the remaining 3 per cent. consists of carbonic acid, hydro- 25 carbons, ammonia, and the helium group of gases, consisting of argon, neon, helium, krypton, xenon and niton. These last named six gases, except niton, are inert under all 30 circumstances and therefore need not be further considered here. Niton is a powerful agent, which will be further described hereinafter. Finally the air may at times contain some ozone.

Oxygen and ozone are the only substances 35 contained in the air that sustain human life. In fact the human being could not live without oxygen. Ozone is now considered to be a condensed form of oxygen, but not many years ago it was considered a combination 40 of electricity and oxygen. It exists but sparingly in the air and is easily dissipated. A little ozone is produced in every battery on the positive pole, as well as in the electrolysis of water, however in 45 very minute quantities. It is claimed that ozone is even more beneficial to sustain human life than oxygen. A proper supply of pure oxygen, available in about the same proportions as found in the atmosphere, 50 is therefore an absolute necessity on a submarine boat, especially while the same is under water and cut off from the atmospheric air. This supply of oxygen, for the submarine boats, as well as for many other

purposes is produced in different ways, by 55 chemical processes and also by electrolysis. The former processes take the oxygen, in most cases, from the air, but all of such processes give a more or less impure oxygen, which may, however, be purified by a second 60 process. But all of such processes could not very well be carried out on board of a submarine for many reasons. Especially could they not be employed while the boat is submerged. Moreover such methods do not 65 furnish the oxygen continuously, or as required by consumption, unless kept in large supply tanks, etc.

For the above reason, and other reasons, not mentioned in these specifications, 70 electrolysis has been adopted. The decomposition of water H_2O by an electric current, known as electrolysis, into its two elements oxygen and hydrogen, has been known for a long time. In this process oxygen is set free 75 on the positive pole, also called the anode, and hydrogen is developed or set free on the negative pole, also called cathode.

However, on board of a submarine, free 80 hydrogen is an element of great danger as will be explained further on, and to eliminate, at least in part, this dangerous element hydrogen and other dangerous gases, is the 85 object of these specifications. I have found from experience that a compound cathode consisting of palladium sponge or palladium black with some rhodium, are the materials which absorb the largest volumes of hydrogen. The catalyst rhodium, although it absorbs some hydrogen is more important in 90 the compound cathode as a catalyst, than as an absorber of hydrogen. When such a cathode has become saturated with hydrogen and then submerged into a solution of ammonium persulfate, or any other solution 95 that is capable of giving off oxygen, the catalyst rhodium will at once cause a union between the hydrogen of the cathode and the oxygen of the solution, and thus restore the cathode into a condition in which it will 100 absorb hydrogen again. But a cathode of palladium, in its different forms, without the rhodium, would never yield up all its hydrogen in such a solution. This feature, 105 to be able to depolarize a cathode and to bring it back to *status quo* in a shorter time, even when the submarine is deep under water, and thereby continue the development

of oxygen continuously is certainly a very important feature and certainly is new and useful, and is my invention.

For the anode, I prefer, the same compound plate as has just been described for the cathode for the following reasons: The compound palladium sponge-rhodium plates do not absorb any oxygen, but deliver all the oxygen generated, hence they do not tarnish, and if perchance any hydrogen is carried along with the developed oxygen, the former is, or likely will be, absorbed by it, and finally, having both anode and cathode identical in shape and composition, all possible danger of misplacing them is completely removed. Moreover such plates are almost indestructible; and therefore are the cheapest plates in the end, although their first cost is higher than common plates.

For the solution, or electrolyte, the best and safest to choose is pure water, with enough sulfuric acid added to make it conductive of the electric current. The arrangement of anode and cathode in electrolysis is too well known to need any further description here. It may be of some advantage to state here that when both plates are submerged into the electrolyte so that the upper edge of them are an inch or more below the water's surface, the condition of both can at a glance be observed. Thus the anode gives off oxygen in bubbles, which indicates the condition of the process. Bubbles of hydrogen on the cathode indicate that the cathode is about polarized and should be replaced by a new one. The space between the top of the plates and liquid surface serves as a purifier of the escaping oxygen also. By using pure water for the elec-

trolyte the most of the poisonous gases are eliminated, such as chlorin, etc., but the explosive gases, such as hydrogen and hydrocarbons, which are produced from other causes, still exist. Hydrogen acting upon the exhaled carbon gases and atmospheric nitrogen with which it intermingles forms several hydro-carbon products which are very explosive and are as dangerous as hydrogen alone.

The elimination of these dangerous and explosive gases forms a new subject for a new application and can therefore not be further considered here.

Having thus fully, clearly and exactly described my invention, 55

I claim:

1. A compound electrode consisting of a hydrogen absorbing substance and a catalyst adapted to render said electrode capable of giving up its hydrogen when brought into contact with oxygen contained in solution. 60

2. A compound electrode consisting of hydrogen-absorbing palladium, and the catalyst rhodium adapted to render said palladium capable of giving up its hydrogen when brought into contact with oxygen contained in solution. 65

3. A compound electrode consisting of hydrogen-absorbing palladium in porous form, and the catalyst rhodium adapted to render said palladium capable of giving up its hydrogen when brought into contact with oxygen contained in solution. 70

JOHN F. SANDERS.
